HAND LOOM

Rhoda C. Jones and William B. Craft,
Manchester, KY.

Application March 12, 1942, Serial No. 434,420

4 Claims. (Cl. 139—29)

This invention relates to a hand loom of very simple construction, which is capable of being economically manufactured and sold, and which can be readily used by a person having no skill in weaving.

Another aim of the invention is to provide a hand loom that can be constructed in a plurality of sizes, including miniature or toy looms to be used by children for weaving.

More particularly, it is the aim of the invention to provide a hand loom having a single heddle of very simple construction and which operates to move alternate warp threads either above or below the normal plane of the warp threads for forming the shed either above or below the normal plane of the threads.

Other objects and advantages of the invention will hereinafter become more fully apparent from the following description of the drawings, which illustrate a preferred embodiment thereof, and wherein: Figure 1 is a top plan view of a loom constructed in accordance with the invention, Figure 2 is a side elevational view of the same, Figure 3 is a longitudinal vertical sectional view taken substantially along a plane of the lines 3—3 of Figure 1, Figures 4 and 5 are cross sectional views taken substantially along the plane of the lines 4—4 and 5—5, respectively, of Figure 1, and Figure 6 is a top plan view of one end of the loom and showing the woof applied to the warp threads by means of a conventional shuttle.

Referring more particularly to the drawings, wherein like reference characters designate like or corresponding parts throughout the different views, 10 designates generally the hand loom, comprising the invention, in its entirety.

Loom 10 includes a frame 11 formed of side plates 12 connected by a plurality of spacing bars 13, which hold the plates 12 in upright and substantially parallel relationship to each other. A cloth beam 14 is provided with restricted ends 15 which are journaled in plates 12, at one end of the frame 11. Cloth beam 14 is provided with radially projecting handles 16, near one end thereof, by which the cloth beam can be turned. An upper warp beam 17 is provided with restricted ends 18 which are journaled in the plates 12, adjacent the opposite end of the frame 11. A lower warp beam 19 has restricted ends 20 which are journaled in the plates 12, below and adjacent the warp beam 17. Cloth beam 14 is provided with a plurality of studs or fastenings 21 by means of which corresponding ends of a plurality of warp threads 22 are attached to the beam 14. Alternate threads 22 have their oppo-

site ends connected to and wound on the upper warp beam 17 and the remaining warp threads 22 are similarly connected to and wound on the lower warp beam 19. Warp beams 17 and 19 are provided with handles 16, near opposite ends thereof, corresponding to the handles 16 of the cloth beam 14. A guide roller 23 is journaled in the plates 12 and is disposed in the frame 11 above and adjacent the cloth beam 14, and the warp threads 22 are trained over the roller 23. A similar roller 24 is journaled in the plates 12 and is disposed in the frame 11 above and adjacent the upper warp beam 17. The warp threads 22, which are wound on the beam 17, are trained over the roller 24, which is disposed at substantially the same level as the roller 23, and the warp threads 22, which are wound on the beam 19, pass beneath the roller 24 and are spaced therefrom, as best seen in Figure 3.

The ends 15, 18 and 20 project from the outer sides of the plates 12 and one of each of said ends is provided with a brake, designated generally 25. The brakes 25 each include an elongated strip, preferably of metal, forming a brake band 26. Band 26 has one end anchored by means of fastening 27 to the frame 11 and a threaded bolt 28 extending through and projecting from the opposite end thereof. An abutment 29 is secured to and projects outwardly from the frame 11 and the bolt 28 extends loosely therethrough and is provided with a wing nut 30 which bears against the outer side of the abutment 29. An intermediate portion 31 of the band 26 is bent to arcuate form and engages around a portion of an end 15, 18 or 20. By tightening the nut 30 portion 31 will be drawn into frictional engagement with the end, which it engages, for holding the beam 14, 17 or 19, with which it is associated, against rotation in the frame 11.

A shaft 32 has restricted ends 33 which extend through and are journaled in the plates 12. Shaft 32 is disposed between and slightly below the level of the rollers 23 and 24. An elongated plate 35 is slotted laterally from adjacent one longitudinal edge thereof to the opposite edge thereof to form a comb having a plurality of tines or arms 36. The plate or comb 35 is bent intermediate of its longitudinal edges into angular form so that the opposite ends of the tines 36 are disposed substantially at right angles to one another. A portion of the shaft 32, between the plates 12, is divided longitudinally to form a removable section 37 which is detachably connected to the shaft 32 by fastenings 38. The free ends of the tines 36 are disposed between the

shaft 32 and its removable section 37 and are clamped therebetween by the fastenings 38 to support the comb 35 so that the tines 36 project outwardly from the shaft 32 and then upwardly. The tines 36, near their apexes and in the portions thereof which are radially disposed relatively to the shaft 32, are provided with openings or eyes 39 through which the threads 22, which are wound on the beam 19, loosely extend. Levers 40 are attached to the ends 33 of the shaft 32, on the outer sides of the plates 12, and project outwardly therefrom for oscillating the shaft 32. A stop 41 projects outwardly from each plate 12 to engage and limit swinging movement of the levers 40 in a direction for raising the comb 35 so that the comb cannot be moved above its dotted line position in Figure 3.

A rod 42 is disposed above each of the plates 12 and has downturned ends which are secured in the upper edge of a plate 12. Rods 42 are disposed intermediate of the ends of the frame 11 and extend to points adjacent the roller 23. A beater or reed 43 includes an elongated, substantially rectangular frame 44 the upper rail of which is provided with extensions forming handles 45. The shanks of the handles 45 are provided with openings 46 which slidably engage rods 42 for supporting the reed 43 transversely of and within the frame 11 and for mounting the reed for a longitudinal sliding movement in the frame. The reed 43 depends downwardly and is provided with spaced perpendicular rods or wires 47 which extend between the threads 22, as best seen in Figure 4. The reed 43 is disposed between the guide roller 23 and the shaft 32. Upper edges of the plates 12 are provided with arcuately shaped recesses 48, between the roller 23 and the shaft 32.

From the foregoing it will be obvious that the brakes 25 and the warp beams 17 and 19 can be loosened to provide sufficient slack in the warp threads 22. The threads 22, which are wound on the lower warp beam 19, are provided with sufficient slack so that these threads can be moved to their full line or dotted line positions of Figure 3. When properly tensioned, warp beams 17 and 19 are held against rotation by applying the brakes 25, which are associated therewith. When the levers 40 are moved to their full line position of Figure 3 the threads 22, which are connected to the beam 19, will be disposed below the other threads 22 to form the passage or shed, below the normal plane of the threads. When the levers 40 are moved to their dotted line position of Figure 3 these threads, which engage the comb 35, will be disposed above the plane of the other threads 22 to form the passage or shed thereabove. In Figure 6 the woof is shown at 49 after having been passed a plurality of times alternately through upper and lower passages or sheds, as previously described, by means of a conventional shuttle 50. The weaving operation, illustrated in Figure 6, is conventional. The recesses 48 are provided to permit the passage of the shuttle 50 back and forth through the frame 11. The reed 43 is normally disposed between the comb 35 and the woof 49 and is adapted to be slid toward the woof so that the wires 47 will engage the woof to pack the rows thereof closely together. From time to time all three of the brakes 25 are released so that the cloth beam 14 can be revolved by its handle 16 for winding cloth onto said beam.

From the foregoing it will be readily apparent that only one-half of the warp threads 22 are

raised and lowered and for this reason two warp beams must be provided, due to the difference in the amount of slack between these threads and the stationary threads 22. The eyes 39 are made sufficiently large so that the threads 22 of different thicknesses can readily be passed therethrough. It will also be readily apparent that the stationary threads will extend through the spaces between the tines 36 so as not to interfere with the movement of the heddle, designated generally 51, and which is formed by the shaft 32 and the comb 35.

Various modifications and changes are contemplated and may obviously be resorted to, provided they fall within the spirit and scope of the invention as hereinafter defined by the appended claims, as only a preferred embodiment of the invention has been disclosed.

We claim as our invention:

- 20 1. A loom comprising a frame, a cloth beam mounted in one end of the frame and to which corresponding ends of a plurality of warp threads are adapted to be attached, a warp beam mounted in the opposite end of said frame and to which the opposite ends of alternate warp threads are attached, a second warp beam mounted in said last mentioned end of the frame and below the first mentioned warp beam and to which the opposite ends of the remaining warp threads are attached, a shaft journaled in said frame intermediate the ends thereof for oscillation, a plurality of arms projecting radially from the shaft to form a heddle, said arms having portions radial with respect to said shaft provided with eyes 35 adjacent their outer ends through which said last mentioned warp threads are adapted to loosely extend, said arms having angular portions rising from said portions spaced from one another and being disposed for movement between the first 40 mentioned warp threads, and such shaft functioning through oscillation to raise or lower the last mentioned warp threads to form the shed either above or below the normal plane of the warp threads.
- 45 2. A loom as in claim 1 having arched guide rods supported by said frame provided with portions disposed above and longitudinally of the sides thereof, and a reed or beater slidably supported by said portions of the guide rods and depending into the frame and through which the warp threads extend.

- 50 3. A loom as in claim 1 wherein the frame has upstanding side members, arched guide rods rising from the upper edges of said side members and over said heddle, a beater slidably mounted by said guide rods, said side members being recessed in their upper edges below the guide rods to facilitate operation of a shuttle.

- 55 4. In a loom, a heddle comprising an oscillating shaft, a comb member connected to said shaft longitudinally thereof, said member comprising tines each having portions which are at an angle to each other and one of which portions projects radially from the shaft, the radially projecting portion having eyes for the warp threads of the loom, said member having slots between the tines, and said slots being adapted to receive the other warp threads, oscillation of said shaft functioning for raising and lowering the first-mentioned threads relatively to the last-mentioned threads to form the shed.
